B. H. Mason

Cutting Railroad-Track Irons.

N° 26, 441.

Patented Dec. 13, 1859.

THE GRAPHIC CO. PHOTO-LITH. 39 & 41 PARK PLACE, N.Y.

UNITED STATES PATENT OFFICE.

BENJAMIN A. MASON, OF NEWPORT, RHODE ISLAND.

MACHINE FOR CUTTING RAILWAY-BARS.

Specification of Letters Patent No. 26,441, dated December 13, 1859.

To all whom it may concern:

Be it known that I, BENJAMIN A. MASON, of Newport, in the State of Rhode Island, have invented a new and useful Machine for 5 Cutting the Ends of Railroad-Rails for Splicing Them by a Species of Lap-Joints; and I do hereby declare that the following is a full, clear, and exact description thereof, reference being had to the accompanying 10 drawings, making part of this specification, in which—

Figure 1 represents the two ends of rails after having been cut to the form required to produce the intended splice; Fig. 2, is a 15 side elevation of the machine; Fig. 3, a vertical section taken at the line A, a, of Fig. 2; and Fig. 4, a horizontal section taken at the line B, b, of Fig. 3.

The same letters indicate like parts in all 20 the figures.

The object of my invention is to cut the ends of T rails for railroads so as to form the kind of lap joint represented in Fig. 1, and the better to understand the operation 25 of my said invention I will describe the kind of lap joint by which the rails are to be united. But I wish it to be understood that this kind of lap joint for uniting the ends of the sections of rails is not of my invention.

I form one end of a section (A) of a T rail by cutting out one half of its thickness for a distance of about six inches from the end and about two thirds the depth from the tread or upper surface to the bottom or the 30 under face of the web, so that the recess formed will present a longitudinal vertical face (a') in the plane of the middle of the thickness of the rail. The extreme end of the rail will present a plane at right angles 35 to the longitudinal plane of the rail; and the inner end of the recess a vertical face (d') parallel with the end. And the bottom of this recess will present a plane (b') which longitudinally is parallel with the tread or 40 upper surface of the rail, and transversely a plane at an inclination to the base so as to be lowest at its junction with the central vertical face (a') and inclining upward to the outer surface of the rail, so that at the 45 cross section this recess will present one half of what is known as a dovetail rabbet. At a distance of one half the length of this recess from the end I cut away the lower part or web of the rail to form the plane (b') in 50 a vertical plane (c') at right angles to the longitudinal plane of the rail, and the under

face of the part which projects beyond the cross vertical plane (c') I cut to a plane (b'') the exact reverse of the before described plane (b') so that the cross section 60 of this projecting part will present one half of what is termed a dovetail tenon.

Having thus cut one end of a section of rail I cut or form the adjacent end of the next section the exact reverse thereof, so 65 that the central longitudinal vertical plane (a') of the one will come in contact with the corresponding plane of the other, the end of the projecting part of the one against the cross vertical plane (d') at the end of 70 the recess of the other, the transverse inclined under face or plane (b'') of the one onto the inclined bottom (b') of the recess of the other, and the cross vertical plane (c') of the web of one against the corresponding plane of the other, so that when 75 put together the two sections will be completely locked, and prevent each other from moving vertically or laterally.

In the accompanying drawings (a, a) 80 represent ways to which are fitted a suitable carriage (b) adapted to receive and hold a T rail, as it is termed by railroad engineers, there being suitable clips (c, c, c, c) on the carriage to extend over the web of the rail 85 to hold it down to the surface of the carriage. This carriage is moved forward by a screw shaft (d) below the ways, the thread of which acts on a projection at the bottom of the carriage. The end of the screw shaft 90 has a cog wheel (e) which is turned one cog at each rotation of the main driving shaft (f) by a single spur on a wheel (g) on the said driving shaft. Or the feeding motion may be imparted by any other suitable mechanical means adapted to imparting an intermittent feeding motion at the end of each complete operation of the series of cutters to be presently described.

In the frame (h) beyond the ways (a, a) 100 are mounted the stocks of four cutters (i, j, k, l) adapted to slide in suitable ways as represented. The stock of the cutter (i) has a connecting rod (m) the upper end of which embraces an eccentric (n) by which 105 the cutter is operated to give a vertical reciprocating motion to cut into the rail as it is presented by the feeding motion of the carriage, beginning at the end and by a succession of cuts removing the metal to 110 form a rabbet, and leave the vertical plane (d') parallel with the end of the rail, and

the longitudinal vertical plane (a') in the middle of the breadth of the rail. This cutter is formed with a cutting edge at the lower end of its front face to make the cuts parallel with the face (d') and at right angles with the plane (a') of the rabbet or recess. As the cutter (i) begins to rise out of the way the cutter (j) moves forward to insure the removal of the chip from and give the required face to the plane (a') of the rabbet. This cutter projects from its stock (o) which slides horizontally in suitable ways, the motion being imparted by an eccentric (p) as in the case of the cutter (i) 15 by a connecting rod (q). This cutter is formed with its lower horizontal edge to go down to the bottom of the rabbet in the rail, its cutting edges corresponding with the vertical plane (a). And just as the cutter (j) 20 is completing its cut, the third cutter (k) begins to advance so as to complete its cut just after. The cutter (k) projects from its stock (r) which slides in suitable ways at right angles to the longitudinal axis of the 25 rail and at an inclination with the base of the rail to correspond with and form the inclined bottom (b') of the recess in the rail. The stock of this cutter is connected with and receives motion from an eccentric (s) 30 in the like manner as the other cutters. And the fourth cutter (l) which is mounted on a stock (t) like the cutter (k) and which receives motion in like manner from an eccentric (u) is placed on the opposite side of 35 the rail and placed on an equal but reversed inclination, cuts away the under part of the rail to form the beveled under portion of the rail which projects beyond the cross vertical plane (c') to fit onto the inclined bottom

(b') of the recess to be formed in the adjacent section of rail.

Motion is imparted to the eccentrics for operating the three cutters (i , k , l) by means of a pinion (v) on the main driving shaft which pinion engages the cogs of three 45 wheels (w , w , w) one on each of the shafts of the said eccentrics. And the required motion is imparted to the eccentric of the horizontal cutter (j) by two bevel wheels (x , y) one on the main driving shaft and 50 the other on the shaft of the eccentric. In this way a series of cutters and the successive cutting operation of each as the rail is presented and gradually advanced by the intermittent feed motion the ends 55 of the sections of rails are formed in the manner described to form a splice or lap joint the excellence of which has been fully recognized but which has not gone into general use for the want of suitable machinery 60 for giving at little cost the required form to the ends of the sections of rails.

I do not wish to be understood as limiting my claim of invention to the mechanical arrangement for imparting motion to the several cutters or the carriage as other and equivalent means may be substituted.

What I claim as my invention and desire to secure by Letters Patent for giving to rails the form substantially such as herein 70 described, is—

The combination of the series of cutters arranged in relation to each other substantially as described.

B. A. MASON.
